[57] **CLAIM**

The ornamental design for a combination cash-handling machine and banknote dispensing cassette, as shown and described.

DESCRIPTION

FIG. 1 is a top, front, right side perspective view of a combination cash-handling machine and banknote dispensing cassette showing our new design, the top of the cash-handling machine being in an open condition, exposing the banknote dispensing cassette in an alternate position of use; FIG. 2 is a top, front, left side perspective view of the cash-handling machine of FIG. 1 shown in a closed condition;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a top, front, right side perspective view of the banknote dispensing cassette of FIG. 1, shown separated from the combination cash-handling machine and banknote dispensing cassette for ease of disclosure;

FIG. 10 is a front elevational view of the cassette of FIG. 9;

FIG. 11 is a rear elevational view of the cassette of FIG. 9;

FIG. 12 is a top plan view of the cassette of FIG. 9;

FIG. 13 is a bottom plan view of the cassette of FIG. 9;

FIG. 14 is a left side elevational view of the cassette of FIG. 9;

FIG. 15 is a right side elevational view of the cassette of FIG. 9;

FIG. 16 is a bottom perspective view of the banknote dispensing cassette, shown in a reduced scale in an alternate position of use;

FIG. 17 is a fragmentary front perspective view of the banknote dispensing cassette with the handle in an open condition for ease of disclosure;

FIG. 18 is a bottom, front, right side perspective view of the banknote dispensing cassette in an open condition for ease of disclosure;

FIG. 19 is a top, front, right side perspective view of the banknote dispensing cassette in an open condition for ease of disclosure; and,

FIG. 20 is a top, front, right side perspective view of the combined cash-handling machine and banknote dispensing cassette, shown partially broken away for ease of disclosure and shown at a reduced scale in an alternate position of use.

The broken lines disclose environmental structure which is for illustrative purposes only and is not part of the claimed design.
